UNITED STATES PATENT OFFICE.

WILLIAM M. PHELPS, OF MARSHALL, MICHIGAN.

LANTERN-BRACKET.

SPECIFICATION forming part of Letters Patent No. 252,697, dated January 24, 1882.

Application filed June 21, 1881. (Model.)

To all whom it may concern:

Be it known that I, WILLIAM M. PHELPS, of Marshall, in the county of Calhoun, and in the State of Michigan, have invented certain new and useful Improvements in Lantern-Brackets; and I do hereby declare that the following is a full, clear, and exact description thereof, reference being had to the accompanying drawing, and to the letters of reference marked thereon, making a part of this specification.

This invention has for its object to provide a simple, cheap, and convenient attachment whereby a lamp or lantern may be readily attached to a carriage or buggy dash-board or to any other similar fixture. This object I attain by the devices illustrated in the accompanying drawing, which shows a perspective view of my invention.

The letter A indicates a rectangular metallic frame, which may be constructed with a concave reflector, B, if desired. At the sides of said frames are located the wires C, which extend above and below the frame A. The upper ends of the wires C are bent rearward and downward, as indicated by the letter D, and the lower ends are bent forward and provided with hooks E at their extremities. At the upper corners of the frame are pivoted horizontal wires F, having hooks G at their

ends, and at the lower edge of said frame is pivoted a wire, G', the ends of which project and are bent forward and provided with semi-cylindrical bearings H at their ends.

The attachment is secured to the lantern (indicated in the drawing by dotted lines) by placing the bearings H against the lower parts of the uprights at the side of the lantern and securing the hooks G and E to said uprights.

To attach the device with the lamp to the dash-board I, the hooked ends D of the wires C are secured over the upper edge of said dash-board.

Having thus described my invention, what I claim is—

In combination with the frame A, provided with wires C, having hooked ends D and E, the wires F and G', the first mentioned provided with hooks G and the last mentioned with bearings H, the whole adapted to hold a lantern and support the same upon the dash-board of a vehicle or other fixture, substantially as specified.

In testimony that I claim the foregoing I have hereunto set my hand this 11th day of June, 1881.

WILLIAM M. PHELPS.
